[57] CLAIM

The ornamental design for a an insulative cover for use with an automotive type battery, as shown and described.

DESCRIPTION

FIG. 1 is a top and side perspective view of a an insulative cover for use with an automotive type battery showing my new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof;

FIG. 7 is a rear elevational view thereof; and

FIG. 8 is an environmental perspective view with the broken line showing of a battery being for illustrative purposes only and forming no part of the claimed design; and.

FIG. 9 is a perspective view of the article in use.

The broken lines showing an automotive type battery are for illustrative purposes only and form no part of the claimed design.

The contrasting shading on the rectangular elements represents an adhering surface.
